UNITED STATES PATENT OFFICE.

JOHN JAMES SAUNDERS, OF EDMONTON, ALBERTA, CANADA.

AUTOMATIC FORCE-FEED LUBRICATING ATTACHMENT.

Application filed September 26, 1927. Serial No. 222,075.

This invention relates to an automatic force feed lubricating attachment for steam engine cylinders, and has for its object to provide, in a manner as hereinafter set forth, 5 an attachment of the class referred to for feeding lubricant into the cylinder of the engine automatically with the supply of steam from the steam chest to the cylinder, and further for regulating the feed according 10 to the speed and size of the engine cylinder.

Further objects of the invention are to provide, in a manner as hereinafter set forth, an automatic force feed lubricating attachment 15 for the purpose referred to, and which is simple in its construction and arrangement, strong, durable, compact, thoroughly efficient in its use, conveniently installed with respect to the engine cylinder, readily 20 assembled, and comparatively inexpensive to set up.

With the foregoing and other objects in view the invention consists of the novel construction, combination and arrangement of 25 parts as hereinafter more specifically described, and illustrated in the accompanying drawings, wherein is shown an embodiment of the invention, but it is to be understood that changes, variations and modifications 30 can be resorted to which fall within the scope of the claims hereunto appended.

In the drawings wherein like reference characters denote corresponding parts throughout the several views:

35 Figure 1 is a longitudinal sectional view of an engine cylinder, showing the adaptation therewith of an attachment in accordance with this invention, and with the attachment shown in longitudinal section.

40 Figure 2 is a view of the adaptation of the attachment with respect to the engine cylinder and in section at right angles with respect to the showing in Figure 1 and further taken on line 2-2 of Figure 1.

45 Figure 3 is a vertical sectional view of a modified form of lubricant expelling piston and the actuating piston for the latter.

Referring to the drawings in detail 1 denotes an engine cylinder, 2 the piston operating therein and 3, 4 steam intake ports which lead to the piston chamber 5. Arranged on the cylinder 1, is the steam chest 6, having an inlet 8 and a controlling valve 7 for the ports 3, 4. The stem of the piston

2 is indicated at 9 and the stem of the controlling valve 8 is indicated at 10. The chamber formed by the chest 6, and in which operates the valve 8 is indicated at 11.

Leading from the chamber 11, as well as communicating therewith, is a pair of oppositely extending combined steam supply and discharge lines 13, 14, and leading to the chamber 11 is a pair of oppositely extending lubricant supply lines 15, 16. The lines 15 and 16 communicate with the chamber 11 between the lines 13, 14.

Arranged above the steam chest 6 is a housing 17 provided with a pair of partitions 18, 19 to form a lubricant reservoir 20 and a pair of piston chambers 21, 22 and 70 with the latter of greater diameter than the former. The partition 19 is provided centrally thereof with a lengthwise extending slot 23. The partition 18 is formed with a pair of valve seats 24, 25 and leading therefrom for establishing communication between the reservoir 20 and the chamber 21 are ports 26. The ports 26 are controlled by a pair of needle valves 27 which threadedly engage with the top 28 of the housing 17 80 and project a substantial distance thereabove. The top 28 of the housing 17 is formed with a normally closed filling opening 29 provided with a screen 30.

The lubricant feed line 15 extends from 85 one end of the chamber 21 and is provided with a check valve 31. The lubricant feed line 16 extends from the other end of the chamber 21 and is provided with a check valve 32. The check valves are of the well 90 known ball type and the balls have their movement in one direction arrested to prevent closing of the feed lines, when the piston 38 moves to the right or left to expel the lubricant. When the piston 38 moves to the 95 right to expel the lubricant into line 16, the check valve in line 15 closes the latter and when piston 38 moves to the left to expel the lubricant into line 15, the check valve in line 16 closes the latter.

100 Each end wall of the chamber 22, axially thereof is provided with an inwardly extending tubular nipple as indicated at 33, 34. The line 13 communicates with the nipple 33 and the line 14 communicates with 105 the nipple 34. The bottom of the housing 17 is formed with a lengthwise disposed slot 35 which is closed by a removable plate 36.

The bottom of the housing is indicated at 37.

Operating in the chamber 21 is a piston 38 and operating in the chamber 22 is a piston 39 and the latter is of much greater area than the former. The pistons 38 and 39 are connected together by a pin 40 which extends through the slot 23 and the slot 35 provides means whereby the two pistons can be connected together by the pin 40. The piston 38 is operated by the piston 39. Each end of the piston 39 is provided with a socket 41 for the reception of a tubular nipple.

The piston 39 is operated by steam from the chest 6. The operation of the attachment, for the purpose of feeding the lubricant, is timed by the valve 8, and corresponds with the stroke of the piston 2 in the cylinder 1. It will be assumed that steam is supplied to the chamber 22, through the line 13 and will force piston 39 towards the nipple 34 and which forces steam from the cylinder 22 through the line 14 to the chest 6. The exhaust from the chamber 22 is connected to the exhaust of the engine by the position of valve 7. As piston 38 is connected to piston 39 by a pin 40, piston 38 will be carried in the same direction as piston 39 and the oil within the chamber 21 is forced out through the line 16 and into the chest 6 and where it is carried with steam through port 3 into the piston chamber 5. When the pistons 38 and 39 are moving in the direction as stated, the check valve 31 is closed whereby that end of the cylinder 21 which communicates with the chest 6 through the medium of the line 15 is closed to the chest. When piston 38 is at the end of its stroke, it clears port 24 and oil enters into chamber 21 due to partial vacuum therein. When the pistons 38 and 39 move in the opposite direction, lubricant will enter chamber 21 through port 25 as the latter will be open.

The nipples 33, 34 in connection with the sockets 41, act as cushioning means for the stroke of the piston 39 whereby it is prevented from climbing against the ends of the chamber 22. The pockets or sockets 41 in the piston 39 fit over the nipples 33, 34 and trap the exhaust steam between piston face and end of cylinder thereby setting up a cushioning action for piston 39.

When the pistons 38 and 39 move in a direction towards the lines 14 and 16 lubricant is supplied to the steam chest and from there it passes through the port 3 into the piston chamber 5 and when the pistons 38, 39 are moved towards the lines 13, 15 lubricant is supplied into the steam chest and from there it passes through the port 4 into the chamber 5. The lubricant when passing into the engine cylinder mixes with the steam, as it is conducted through the same ports or passages through which passes the steam to the chamber 5.

65 The action of the attachment is automatic

and provides for a thorough lubrication of the piston 2, as well as the valve 8, and therefore it is thought the many advantages of a lubricating attachment, in accordance with this invention, can be readily understood, and although the preferred embodiment of the invention is as illustrated and described, yet it is to be understood that changes in the details of construction can be had which will fall within the scope of the invention as claimed.

In the modified form shown in Figure 3 the lubricant expelling piston 43 is of cylindrical cross section, as well as the actuating piston 44 for the piston 43. The pistons 43 and 44 are connected together by a pin 45 which extends through a slot 47 formed in a partition 46 provided in a housing 48 which is constructed in a manner to provide cylindrical piston chambers 49, 50 for the pistons 43, 44 respectively. The piston 43 is of less diameter than the piston 44. Otherwise than that as stated, the form shown in Figure 3 is the same as that illustrated in Figures 1 and 2.

What I claim is:

1. A lubricating attachment for steam engines comprising a lubricant reservoir having a pair of outlet ports, adjustable means for controlling discharge through said ports, a pair of superposed piston chambers, said reservoir arranged over said chambers and said ports discharging lubricant into the upper one of said chambers at two points thereof, a piston operating in each of said chambers and connected together for moving in unison, the upper one of said pistons constituting a lubricant expelling means and acting to successively open and close said ports and to close said ports simultaneously, a pair of oppositely extending lubricant feed lines leading from the ends of that chamber receiving lubricant and adapted to open into the steam chest of an engine cylinder, oppositely disposed controlling valves for said lines, and a pair of oppositely extending steam lines extended from the ends of the lower one of said chambers and adapted to open into said steam chest and conducting steam for operating the lower one of said pistons in opposite directions thereby providing for the alternate feed of lubricant from the ends of that chamber receiving the lubricant to said steam chest.

2. A lubricating attachment for steam engines comprising a lubricant reservoir having a pair of outlet ports, adjustable means for controlling discharge through said ports, a pair of superposed piston chambers, said reservoir arranged over said chambers and said ports discharging lubricant into the upper one of said chambers at two points thereof, a piston operating in each of said chambers and connected together for moving in unison, the upper one of said pistons con-

- stituting a lubricant expelling means and acting to successively open and close said ports and to close said ports simultaneously, a pair of oppositely extending lubricant feed lines leading from the ends of that chamber receiving lubricant and adapted to open into the steam chest of an engine cylinder, oppositely disposed controlling valves for said lines, a pair of oppositely extending steam lines leading from the ends of that chamber receiving lubricant and adapted to open into the steam chest of an engine cylinder, oppositely disposed controlling valves for said lines, a pair of oppositely extending steam lines extended from the ends of the lower one of said chambers and adapted to open into said steam chest and conducting steam for operating the lower one of said pistons in opposite directions thereby providing for the alternate feed of lubricant from the ends of that chamber receiving the lubricant to said steam chest, and means to provide a cushion for that piston driven by steam supplied from the steam chest.
- 20 3. A lubricating attachment for steam engines comprising a lubricant reservoir having a pair of outlet ports, adjustable means for controlling discharge through said ports, a pair of superposed piston chambers, said reservoir arranged over said chambers and said ports discharging lubricant into the upper one of said chambers at two points thereof, a piston operating in each of said chambers and connected together for moving in unison, the upper one of said pistons constituting a lubricant expelling means and acting to successively open and close said ports and to close said ports simultaneously, a pair of oppositely extending lubricant feed lines leading from the ends of that chamber receiving lubricant and adapted to open into the steam chest of an engine cylinder, oppositely disposed controlling valves for said lines, and a pair of oppositely extending steam lines extended from the ends of the lower one of said chambers and adapted to open into said steam chest and conducting steam for operating the lower one of said pistons in opposite directions thereby providing for the alternate feed of lubricant from the ends of that chamber receiving the lubricant to said steam chest, and means to provide a cushion for that piston driven by steam supplied from the steam chest.
- 25 4. A lubricating attachment for steam engines comprising a lubricant reservoir having a pair of outlet ports, adjustable means for controlling discharge through said ports, a pair of superposed piston chambers, said reservoir arranged over said chambers and said ports discharging lubricant into the upper one of said chambers at two points thereof, a piston operating in each of said chambers and connected together for moving in unison, the upper one of said pistons constituting a lubricant expelling means and acting to successively open and close said ports and to close said ports simultaneously, a pair of oppositely extending lubricant feed lines leading from the ends of that chamber receiving lubricant and adapted to open into the steam chest of an engine cylinder, oppositely disposed controlling valves for said lines, and a pair of oppositely extending steam lines extended from the ends of the lower one of said chambers and adapted to open into said steam chest and conducting steam for operating the lower one of said pistons in opposite directions thereby providing for the alternate feed of lubricant from the ends of that chamber receiving the lubricant to said steam chest, and means to provide a cushion for that piston driven by steam supplied from the steam chest.
- 30 5. A lubricant attachment for steam engine cylinders comprising a lubricant receiver, a pair of lubricant feed lines leading therefrom to the steam chest of an engine cylinder, a piston operating in said receiver for alternately expelling lubricant therefrom into said lines, controlling valves for said lines, a piston chamber, said receiver arranged over said chamber, a slotted wall forming means providing the bottom of the receiver and the top of said chamber, combined steam supply and discharge lines leading from said chamber to the steam chest of the engine, a piston operating in said chamber and driven from steam supplied thereto, and a coupling connection extending through the slot of said wall forming means for connecting the pistons together whereby they will operate in unison when the steam actuated piston is driven.
- 35 6. A lubricant attachment for steam engine cylinders comprising a lubricant receiver, a pair of lubricant feed lines leading therefrom to the steam chest of an engine cylinder, a piston operating in said receiver for alternately expelling lubricant therefrom into said lines, controlling valves for said lines, a piston chamber, said receiver arranged over said chamber, a slotted wall forming means providing the bottom of the receiver and the top of said chamber, combined steam supply and discharge lines leading from said chamber to the steam chest of the engine, a piston operating in said chamber and driven from steam supplied thereto, a coupling connection extending through the slot of said wall forming means for connecting the pistons together whereby they will operate in unison when the steam actuated piston is driven, a lubricant reservoir arranged over said receiver and having its bottom constituting the top of the receiver, said bottom provided with means for

supplying lubricant to said receiver, and adjustable valves for controlling the means for supplying lubricant to the receiver.

7. A lubricant attachment for steam engine cylinders comprising a housing provided with a pair of superposed, spaced partitions to form a lubricant reservoir, an upper piston chamber and a lower piston chamber, the upper of said partitions provided with ports for supplying lubricant from said reservoir to the upper piston chamber, means adjustably engaging with the housing for controlling the supply of lubricant through said ports, a pair of lubricant feed lines leading from the upper piston chamber to the steam chest of an engine, controlling valves for said lines, a piston operating in said upper chamber for alternately expelling lubricant therefrom into said lines, combined steam supply and discharge lines leading from the lower chamber to the steam chest of the engine, a piston operating in said lower chamber and driven from the steam supplied thereto, and a coupling connection extending through the lower of said partitions for connecting the two pistons together to provide for the operation thereof in unison on the actuation of the piston in the lower chamber.

8. A lubricant attachment for steam engine cylinders comprising a housing pro-

vided with a pair of superposed, spaced partitions to form a lubricant reservoir, an upper piston chamber and a lower piston chamber, the upper of said partitions provided with ports for supplying lubricant from said reservoir to the upper piston chamber, means adjustably engaging with the housing for controlling the supply of lubricant through said ports, a pair of lubricant feed lines leading from the upper piston chamber to the steam chest of an engine, controlling valves for said lines, a piston operating in said upper chamber for alternately expelling lubricant therefrom into said lines, combined steam supply and discharge lines leading from the lower chamber to the steam chest of the engine, a piston operating in said lower chamber and driven from the steam supplied thereto, a coupling connection extending through the lower of said partitions for connecting the two pistons together to provide for the operation thereof in unison on the actuation of the piston in the lower chamber, and the piston in the lower chamber and the ends of the latter having co-acting means to provide cushions for said lower piston.

In testimony whereof, I affix my signature hereto.

JOHN JAMES SAUNDERS.
